UNITED STATES PATENT OFFICE.

GUSTAV B. PETSCHÉ, OF PHILADELPHIA, PENNSYLVANIA, ASSIGNOR TO SOUTHWARK FOUNDRY AND MACHINE COMPANY, OF PHILADELPHIA, PENNSYLVANIA, A CORPORATION OF PENNSYLVANIA.

BLOWING-ENGINE.

No. 912,486.

Specification of Letters Patent.

Patented Feb. 16, 1909.

Application filed June 6, 1906. Serial No. 320,395.

To all whom it may concern:

Be it known that I, GUSTAV B. PETSCHÉ, a subject of the Emperor of Germany, residing in the city and county of Philadelphia, in the State of Pennsylvania, have invented a certain new and useful Improvement 5 in Blowing-Engines, of which the following is a true and exact description, reference being had to the accompanying drawings, which form a part thereof.

My invention relates to blowing engines or compressors of the kind in which the ports connecting the compressing cylinder and the receiver are controlled by valves actuated by auxiliary cylinders and pistons, the cylinders being connected with the compressing cylinders so that the increasing pressure in said cylinder is transmitted to the face of the auxiliary piston to move it 15 in a direction to open the delivery valve, the return movement of the piston and the closing of the valve is generally effected by some positively actuated part of the engine, such as a cam.

The object of my invention is to regulate 20 the admission of compressed air to the auxiliary cylinder so that the pressure in said cylinder will only rise high enough to exert a substantial opening force on the auxiliary 25 piston at or immediately before the point where the pressure in the compressing cylinder and receiver are equal. By proceeding in this manner I avoid any injurious strains on the valve or valve actuating mechanism, and the leading feature of my invention 30 consists in placing in the conduit containing the compressing cylinder and auxiliary cylinder a normally seated valve arranged to open under the pressure of air in 35 the compressing cylinder and held to its seat by the pressure of air in the receiver so that the valve will only open where the two pressures acting upon it bear a determined ratio 40 to each other which is less than unity.

Other features of my invention will be best understood as described in connection 45 with the drawings in which it is illustrated and in which—

Figure 1, is a side elevation of a portion 50 of a compressing cylinder showing the valve actuating cylinders in section and such of the connections therewith as are necessary for the understanding of my present inven-

tion. Fig. 2, is a sectional view of one of the valve casings H, taken as on the section 55 line 2—2 of Fig. 3, and Fig. 3 is a sectional view of the same valve casing taken on the line 3—3 of Fig. 2.

A, indicates the compressing cylinder; A', the compressing piston; B, B, the receivers 60 at the ends of the cylinder; C, indicates the gridiron delivery valves controlling the ports at the delivery end of the receiver.

C', is the valve stem which is connected to the piston D, having, as shown, a second 65 piston extension D', connected with it; a cam roller D'', being secured to the double piston between its two heads. The pistons, which are double headed pistons D, D', move in a double headed cylinder E, E', 70 having lateral bearings E, on which moves a cam F, arranged to contact with the cam roller D'', as indicated. The cams F, F, are shown connected by a rod F', which are actuated by proper mechanism connected with 75 the end F''.

G, G, are conduits connecting the compressing cylinder A, with the cylinder ends E, E, as shown, and in this conduit are situated the valve casings H, H, the construction of which is shown in Figs. 2 and 3. The casings are provided with a partition K which supports two valve seats, one indicated at L and the other at M. A movable head N, of the casing is formed with a cylinder N', opening downward and connected at its upper end through the opening N'', with a pipe I, see Fig. 1, connecting in turn with the receiver D, of the engine.

O, indicates a removable head in the lower 90 part of the casing H. P, the main valve normally seated on the seat L, and arranged to be acted up and held to its seat through a piston P', which may conveniently be formed integral with it as shown, and which works 95 in the cylinder E. A light spring Q should be provided to hold the valve to its seat.

R, is a valve normally seated on the seat M and held lightly to its seat by a spring K'. It will be understood that the normal flow 100 of compressed air from the compressing cylinder to the auxiliary cylinder is from the side J, to the side J', of the casing. Assuming the compressing piston to be moving toward the left in Fig. 1, the valve C, at the 105 left hand end of the cylinder is closed and

the valve P, held firmly to its seat by the pressure from the receiver B, connecting through the pipe I, with the cylinder Q, and acting on the piston P'. As the compressing 5 piston moves toward the left the cam F, is withdrawn from contact with the roll D², and the pressure accumulating in the compressing cylinder is transmitted to the under side of the valve P, the valve, however, remaining seated until this pressure has 10 reached a determined ratio to the pressure in the receiver at which point the valve P, will open and admit the compressed air to the auxiliary cylinder E, where, acting on the piston D, it effects a rapid opening of the valve C. The valve P and piston extension P' form in effect a differential piston of which the area at the bottom end of the piston, exposed to the pressure of the side J of the casing H is substantially greater than the area 15 of the end of the piston working in the cylinder N¹. As the spring Q is a light spring, the valve P opens consequently when the ratio of the pressure in the chamber J of the casing H to the pressure in the cylinder N¹ is appreciably less than unity. By proceeding in this manner, it is possible to prevent a rise in pressure in the valve actuating cylinder E to a valve large enough to exert 20 a strong opening force on the piston D until the instant, or but very slightly before the instant when the delivery valve should open, while, on the other hand, the valve P opens early enough in the stroke of the compressing piston to give time for air to 25 pass into the cylinder E and build up the pressure therein at the proper instant to the point necessary to open the heavy delivery valve.

30 It will be understood by those skilled in the art that the ratio between the pressure in chamber J and cylinder N¹ at which the valve P should open, will depend to some extent on the speed at which the engine is run. The light spring Q is therefore so chosen for any particular condition of use 35 as to insure that the valve P will open when the pressure in the seat J of the casing H rises to a ratio with the pressure in the cylinder N¹, which is proper under the circumstances. As soon as the compressing piston has crossed and uncovered the opening of the conduit G, into the cylinder the pressure 40 behind the piston of course falls to atmospheric or less than atmospheric pressure and the compressed air in the cylinder E, can then escape back into the cylinder by raising the valve R, from its seat, and thus enables the valve C, to be closed by the action 45 of the cam F, without undue compression of the air in the cylinder E. The function of the cylinder end E', and piston head D', is simply to serve as a cushioning device in the opening of the delivery valves, the 50 construction being described in former

patents and forming no part of my present invention.

Having now described my invention, what I claim as new and desire to secure by Letters Patent is:

1. The combination in a blowing engine having a compressing cylinder, a receiver, a delivery valve opening and closing communication between said cylinder and receiver, an actuating piston and cylinder for the delivery 75 valve, a conduit connecting the valve actuating and compressing cylinders, and means responsive to the pressure in the receiver and compressing cylinder for preventing air from passing through said conduit to the valve 80 actuating cylinder to open the delivery valve except when the ratio of the pressure in the compressing cylinder to the pressure in the receiver rises to a predetermined value which is appreciably less than unity. 85

2. The combination in a blowing engine having a compressing cylinder, a receiver, a delivery valve opening and closing communication between said cylinder and receiver, an actuating piston and cylinder for the delivery 90 valve, a conduit connecting the valve actuating and compressing cylinder, means responsive to the pressure in the receiver and compressing cylinder for preventing air from passing through said conduit to the valve 95 actuating cylinder to open the delivery valve except when the ratio of the pressure in the compressing cylinder to the pressure in the receiver rises to a predetermined value which is appreciably less than unity, and means 100 acting independently of the receiver pressure for permitting air to flow through said conduit from the valve actuating cylinder to the compressing cylinder.

3. In a blowing engine having a receiver, 105 a gridiron delivery valve opening thereto and a valve actuating cylinder connected to the compressing cylinders as described, a normally seated valve situated in the conduit leading from the compressing cylinder to 110 the valve actuating cylinder, said valve having a surface acted on by the pressure of the air in the compressing cylinder in a direction tending to open said valve, and means for holding the valve to its seat comprising a 115 piston surface smaller than the first mentioned surface and acted on by the pressure of the receiver.

4. In a blowing engine having a receiver, 120 a gridiron delivery valve opening thereto and a valve actuating cylinder connected to the compressing cylinders as described, a normally seated valve situated in the conduit leading from the compressing cylinder to the valve actuating cylinder, said valve having 125 a surface acted upon in a direction to open the valve by the pressure of the air in the compressing cylinder, means for holding the valve to its seat comprising a piston surface smaller than the first mentioned surface 130

acted on by the pressure in the receiver and means for permitting the escape of air from the actuating cylinder during the closing of the delivery valve.

5. In a blowing engine having a receiver, a delivery valve opening thereto, and a valve actuating cylinder connected to the compressing cylinder as described, a conduit leading from the compressing cylinder to the valve actuating cylinder, and means regulating the flow of air from the compressing cylinder to the valve actuating cylinder through said conduit, said means comprising a differential piston having its 10 larger end acted on in the direction to open the conduit by the pressure in the compressing cylinder, and its smaller end acted on in the direction to close the conduit by the pressure of the receiver, and a light spring also

acting on said piston in a direction to close 20 said conduit.

6. In a blowing engine having a receiver, a delivery valve opening thereto and a valve actuating cylinder connected to the compressing cylinders as described, a valve casing 25 H, situated in the conduit connecting the compressing cylinder and valve actuating cylinder, said casing having a main seat L, and supplemental seat M, and a cylinder N', in combination with a conduit connecting 30 cylinder N' with the receiver, a piston working in cylinder N', a valve P, acted on by said piston and normally closing seat L, and a normally seated valve R, closing seat M.
